UNITED STATES PATENT OFFICE.

CHARLES S. BATDORF, OF BROOKLYN, NEW YORK, ASSIGNOR TO AUTOMATIC COIN-WRAPPING MACHINE COMPANY, OF NEW YORK, N. Y., A CORPORATION OF NEW YORK.

PAPER-TUCKING AND WRAPPING MECHANISM.

1,130,244.

Specification of Letters Patent.

Patented Mar. 2, 1915.

Application filed April 11, 1910. Serial No. 554,641.

To all whom it may concern:

Be it known that I, CHARLES S. BATDORF, a citizen of the United States, residing at Brooklyn, county of Kings, State of New York, have invented certain new and useful Improvements in Paper-Tucking and Wrapping Mechanism, of which the following is a full, clear, and exact description.

My invention relates to article wrapping machines such, for example, as the type of coin handling machines illustrated in my Patent No. 998,834, of July 25, 1911. In machines of this type, the articles to be wrapped are assembled upon a suitable stacking mechanism and the stack is then conveyed by suitable carrier or gripper arms to and in engagement with a series of wrapping rolls, by which a suitable wrapper which is interposed across the path of the stack in its travel from the stacking means to the wrapping means, is smoothly and tightly rolled about said stack to form the desired package. It is to be understood, however, that the invention may be applied 25 to any machine of a similar type adapted to wrap articles of circular outline, whether in the form of coins, disks or otherwise.

The object of the invention is the provision of means which shall insure the snug laying of the paper or wrapper around the article or articles to be wrapped, in order to produce a tightly and neatly rolled package. Incidental to this object, the invention contemplates means to insure the holding 35 of the initial end of the wrapper snugly against the package during the first part of the wrapping operation, in order that said end may be snugly tucked between the stack and the following part of the wrapper.

40 In the type of machine illustrated in the application above referred to, means are also provided for crimping in the ends of the wrapper against the ends of the article stack, in order to complete the package.

45 The particular form of this mechanism, however, forms the subject matter of my co-pending application Serial No. 554,642, filed April 11th, 1910.

In the drawings I have illustrated so 50 much of the coin handling machine of the type referred to as is necessary to a full

disclosure of the invention, in which, Figure 1 is a front elevation of a machine of the type referred to, showing the wrapping rolls and coöperating parts, the stacking mechanism being removed for clearer illustration. Fig. 2 is a side elevation of the parts shown in Fig. 1. Fig. 3 is a plan view of one of the wrapper rolls detached, showing the wrapper laying and tucking devices used in conjunction therewith, said parts being shown in stack receiving position. Fig. 4 is a front view of the parts shown in Fig. 3. Fig. 5 is a sectional view on the line 5—5 Fig. 4, looking from the right. Fig. 6 is a view of the wrapping roll alone, which is used in conjunction with the parts illustrated in Figs 3 to 5 inclusive. Fig. 7 is a diagrammatic view illustrating the relative positions of the wrapping rolls, 70 the wrapper laying and tucking mechanism and the wrapper strip when the stack is brought into initial engagement with the wrapper laying and tucking mechanism, and, Fig. 8 is a view similar to Fig. 7, showing the relative position of the parts at the beginning of the wrapping operation by the wrapping rolls.

Referring to Figs. 1 and 2, 1 indicates a part of the frame of the machine carrying 80 the paper feeding and wrapping mechanism on the upper part of which is mounted a support 2 for the paper roll 3, from which the wrappers are supplied. The wrapper strip 4 is automatically fed between the feed 85 rolls 5 and 6 Fig. 2 and over a knife or cutter 7 to a position transverse of the path of the stack of articles as the latter are conveyed from the stacking mechanism to the wrapping mechanism as described in my co-pending application above referred to. In 90 order to position the wrapper strip accurately with reference to the stack to be wrapped, a lateral guide finger 8 is provided supported by an arm 9 suitably mounted upon a transverse bar 10 of the machine frame, said arm 9 being adjustable laterally to accommodate different widths of wrapper strip. 11 indicates a set screw by which 95 said arm may be held firmly in adjusted position.

The wrapping mechanism proper com-

prises a pair of wrapping rolls 12 and 13, which are journaled respectively upon the arms 14 and 15, said arms being relatively adjustable in any suitable manner in order 5 to enable the rolls to operate upon articles of different diameter. The particular manner of mounting the roll carrying arms 14 and 15 and the means for adjusting the same may be similar to that illustrated in 10 my co-pending application above referred to. Overlying the upper feed roll 13 is a transverse guide bar 13^a, which is mounted adjacent said roll in any suitable manner as by providing the same with hooks 13^b en- 15 gaging a shaft 13^c extending transversely of the frame 13^d, upon which the arms 14—15 of said feed rolls are mounted. This guide bar 13^a serves to conduct the upper run of the wrapper strip as it leaves the 20 knife 7 and to deliver the same smoothly to said upper roll 13. Coöoperating with the wrapping rolls 12 and 13 is a third roll 16, Fig. 1, which is journaled in the upper ends of the arm 17 and 18 of a rocking or oscillating frame 19 fixed to a shaft 20 mounted 25 in the lower part of the frame 1, the shaft 20 being provided with a cam arm 21 having a cam roll 22 adapted to engage the rotary cam 23 carried by a shaft 24 which is 30 operatively connected with the power shaft of the machine. By this construction it will be seen that the third or forward wrapping roll 16 will be caused to move periodically into and out of operative position with respect to the wrapping rolls 12 and 13. As 35 described in my co-pending application, the movement of the third or forward roll 16 to such operative position takes place just after the stack of articles to be wrapped has 40 been conveyed from the stacking device substantially into operative position in engagement with the wrapping rolls 12 and 13 by means of the stack carrier or gripping arms. These carrier or gripping arms may be con- 45 structed and operated in substantially the same manner as illustrated in my patent above referred to. For complete illustration of this invention, however, these carrier arms are indicated at 16^a and are adjustably 50 mounted respectively with the arms 16^b of the rocking frame 16^c. Said frame is suitably connected with suitable cam mechanism by which the gripper arms and the article or stack of articles carried thereby, may be 55 conveyed from the stacking mechanism to the wrapping rolls as described in said patent.

Mounted upon the shaft 16', Fig. 3, of the third or forward wrapping roll 16 is a 60 wrapper laying and tucking device comprising a frame consisting of the end-plates 25—25, connected by the cross plate 26, preferably formed integrally with said end plates. Pivoted upon a shaft 27 mounted 65 between the end plates 25 is a paper laying

blade 28, which is normally held by the coil spring 29 in the position indicated in Fig. 5, in which position it is held against the tension of the spring by a stop arm 29^a, secured to one of the end plates 25. Upon the free edge of the paper laying blade 28 is mounted a wrapper contact bar 30 pivoted at 31 Fig. 3 on said blade, whereby said bar may accommodate itself to the position of the wrapper when the same is brought into engagement therewith and may contact with the said wrapper throughout its entire width in order to lay the same smoothly and snugly about the stack of articles to be wrapped. Upon the opposite side of the 70 roll 16 from the paper laying blade 28 is a rocking frame comprising arms 32 pivoted upon a shaft 33, also fixed between the end plates 25 of the paper laying and tucking frame, and a cross bar 34 connecting the 75 upper ends of said arms 32. Upon the free edge of said frame is pivotally mounted a wrapper laying and tucking blade 35 having the fingers 35^a projecting from its free edge, which fingers lie within the annular slots or 80 recess 16^x in the wrapping roll 16. The frame carrying the tucking blade 35 is held normally in the stack receiving position as indicated in Fig. 5 by means of the coil spring 37^a. This manner of yieldingly 85 mounting the paper tucking blade 35 enables said plate to open out from the wrapping roll 16 in order to accommodate itself to stacks of articles of different diameters which are to be wrapped and at the same 90 time to hold said tucking blade in position to tuck the wrapper snugly against said stack in the manner hereinafter to be described. As the stack A, Figs. 7 and 8 of 95 articles to be wrapped is carried past or over 100 the feed roll 16 as indicated diagrammatically in Fig. 7 by the gripper or stack carrying arms 16^a, said stack carries the wrapper strip 4, which has previously been fed across its path into engagement with the 105 contact bar 30 of the paper laying blade 28. Further movement of the stack A in its travel toward the feed rolls 12—13, serves to rotate the paper laying and tucking frame 110 with the parts carried thereby upon the 115 shaft of the roll 16 until said frame and parts assume the position indicated dia- 120 grammatically in Fig. 8. During this ro- 125 tative movement of said frame, the paper tucking blade 35 carries the extreme end of the wrapper strip 4 against the stack A and holds the same snugly upon said stack as indicated in Fig. 8, whereby said end may be smoothly and tightly received be- 130 tween the stack and the following portion of the wrapper strip 4. The fingers 35^a lying in the annular slots 16^x of the feed roll 16 serve effectively as guides for the initial end of the paper wrapper strip and prevent the same from being caught between the 135

roll 16 and the paper laying and tucking frame. Also the curve of the tucking blade is such that engagement of the stack therewith will cause the outer edge 35^b of said 5 blade to carry the end of the wrapper strip against the stack and hold the same in such position until such end is received between the stack and the following portion of the wrapper. Also during the rotative movement 10 of the tucking or wrapping frame, the paper laying blade 28 is moved inwardly by the stack toward the wrapping roll 16, thereby further laying the wrapper strip snugly and smoothly around the stack. 15 It is understood that as soon as a sufficient amount of the wrapper strip has been fed over the knife 7 to form a wrapper for the stack, the wrapper feeding operation ceases, whereby that portion of the wrapper strip 20 which has already been fed for wrapping purposes is automatically severed from the balance of the strip at the starting of the wrapping operation of the wrapping rolls. 25 As soon as the wrapper is laid completely about the stack by operation of the wrapping rolls, the ends of said wrapper are crimped in against the ends of said stack by means of the crimping fingers 36 mounted between the wrapping rolls 12 and 13, 30 Figs. 1 and 2, which are automatically moved inwardly against the ends of the stack by suitable mechanism, the particular form of which forms no part of the present invention. For the purpose of a 35 clear understanding of this invention, however, it may be said that the crimping fingers 36 are carried upon blocks 37, slidably mounted upon a bar 38 supported at either end by arms 39, depending from rock arms 40, which are pivoted upon studs 41 carried by suitable slides as described in my co-pending application, Ser. No. 544,642 above referred to, by which said crimping arms may be adjusted to accommodate themselves 45 to the different diameters of the articles to be wrapped. To move the crimping fingers inwardly against the ends of the stack, the supports thereof are provided with depending forks or arms 42, which are connected by cam operated arms 43 slidably mounted upon a shaft 44 extending transversely of the machine, and carrying cam rolls 45 which engage suitable cams 46 as described in my co-pending application 50 above referred to. After the wrapping and crimping operation has been completed, the stack is removed from between the feed rolls by a retractive movement of the frame carrying the roll 16 under the influence of the cam arm 21 of the cam 23 hereinbefore referred to and by retraction of the gripper arms whereby the article or stack of articles 55 may be delivered to a suitable receptacle, as described in my patent above referred to.

It will be seen from the above description that the paper laying and tucking mechanism is automatically rotated from stack receiving position to paper laying and tucking position by the stack during its travel into 70 the operative position between the feed rolls, and that during said rotative movement of the paper laying and tucking mechanism, the paper laying blade and the paper tucking blade automatically perform their functions of snugly and tightly laying and tucking the wrapper about said stack. 75

While I have herein described a particular embodiment of my invention, it is to be understood that the same may be varied in 80 detail and relative arrangement of parts, within the scope of the appended claims.

What I claim is:

1. In an article wrapping machine, the combination with a wrapper supply mechanism, of a plurality of wrapping rolls including a roll movable toward and from the other or others, wrapper laying and tucking mechanism comprising a member adapted to lay said wrapper smoothly about said 85 article or articles, and a second member adapted to guide the leading end of said wrapper between said article or articles and the following portion of the wrapper during the wrapping operation, said laying and 90 tucking mechanism being carried by said movable roll and adapted to be operated by the article or articles during the travel of said roll to wrapping position. 95

2. In an article wrapping machine, the combination with a wrapper supply mechanism of a plurality of wrapping rolls, wrapper laying and tucking mechanism carried axially by one of said rolls and comprising a frame having a member adapted to lay 100 said wrapper smoothly about said article or articles and a second member adapted to guide the leading end of said wrapper between said article or articles and the following portion of the wrapper during the wrapping operation. 105

3. In an article wrapping machine, the combination with a wrapper supply mechanism of a plurality of wrapping rolls, wrapper laying and tucking mechanism carried 115 by one of said rolls and comprising a frame rotatably mounted thereon, said frame having a member adapted to lay said wrapper smoothly about said article or articles and a second member adapted to follow said first 120 member in said rotative movement and to guide the leading end of said wrapper snugly against said article or articles and between the latter and the following portion of said wrapper during the wrapping operation. 125

4. In an article wrapping machine, the combination with wrapper supply mechanism, of a plurality of wrapping rolls, means for conveying the articles to said rolls, and 130

means operated by said conveying means and acting by direct contact with the articles in their travel to wrapping position to lay the wrapper snugly about said article or articles and to guide the leading end of said wrapper between said article or articles, and the following portion of said wrapper during the wrapping operations.

5. In an article wrapping machine, the combination with a wrapper supply mechanism of a plurality of wrapping rolls, wrapper laying and tucking means carried axially by one of said rolls comprising a member adapted to lay said wrapper snugly about said article or articles and a second member adapted to guide the leading end of said wrapper between the article or articles and the following portion of said wrapper during the wrapping operation, said 10 laying and tucking mechanism being constructed to be operated by engagement of the article or articles therewith during the travel of said article or articles to operative position between said rolls.

25 6. In an article wrapping machine the combination with a wrapper supply mechanism of a plurality of wrapping rolls, wrapper laying and tucking mechanism rotatably carried by one of said rolls and comprising 30 a member adapted to lay the wrapper smoothly about said article or articles and a second member adapted to guide the leading end of said wrapper between the article or articles and the following portion of said 35 wrapper during the wrapping operation, said first member being arranged to be engaged by said article or articles during the travel of the latter to operative position between said rolls to effect the laying and tucking 40 operation.

7. In an article wrapping machine, the combination with a wrapper supply mechanism of a plurality of wrapping rolls adjustable to articles of different diameters and 45 means adjustable with and coöperating with said rolls to lay the wrapper snugly about said article or articles and to guide the leading end of said wrapper between the article or articles and the following portion of said 50 wrapper during the wrapping operation.

8. In an article wrapping machine, the combination with a wrapper supply mechanism of a plurality of wrapping rolls adjustable to engage articles of different diameter and means for laying the wrapper snugly about said article or articles and means for tucking the leading end of said wrapper between said article or articles and the following portion of said wrapper during 55 the wrapping operation, said laying and tucking means being adjustable with the adjustment of said rolls to articles of different diameters.

60 9. In an article wrapping machine, the

combination with a wrapper supply mechanism of a plurality of wrapping rolls adjustable to engage articles of different diameters, wrapper laying and tucking mechanism carried by one of said rolls and comprising a member adapted to lay said wrapper snugly about said article or articles and a second member adapted to guide the leading end of said wrapper between said article or articles and the following portion of said wrapper during the wrapping operation, 75 said members being relatively movable to engage articles of different diameters.

10. In an article wrapping machine, the combination with a wrapper supply mechanism of a plurality of wrapping rolls, means 80 axially carried by one of said rolls to lay the wrapper snugly about said article or articles and to guide the leading end of said wrapper between said article or articles and the following portion of said wrapper during 85 the wrapping operation and means adjacent one of said rolls to cause smooth delivery of the wrapper to said rolls.

11. In an article wrapping machine, the combination with a wrapper supply mechanism of a plurality of wrapping rolls, means carried by one of said rolls to lay the wrapper snugly about said article or articles and to guide the leading end of said wrapper between said article or articles and the following portion of the wrapper during the wrapping operation and a guide member extending transversely in the path of the wrapper adjacent one of said rolls to cause smooth delivery of the wrapper to said 100 rolls.

12. In an article wrapping machine, the combination with a wrapper supply mechanism of a plurality of wrapping rolls, means carried by one of said rolls to lay the wrapper 105 snugly about said article or articles means to guide the leading end of said wrapper between said article or articles and the following portion of the wrapper during the wrapping operation and means adjacent the path 110 of said wrapper to guide the same to said rolls.

13. In an article wrapping machine, the combination with a wrapper supply mechanism of a plurality of wrapping rolls, means 115 carried by one of said rolls to lay the wrapper snugly about said article or articles means to guide the leading end of said wrapper between the article or articles and the following portion of the wrapper during 120 the wrapping operation, and means for securing the ends of said wrapper upon said article or articles.

14. In an article wrapping machine, the combination with a wrapper supply mechanism of a plurality of wrapping rolls and 125 means carried by one of said rolls to lay the wrapper snugly about said article or articles

and to guide the leading end of said wrapper between said article or articles and the following portion of the wrapper during the wrapping operation, and means for crimping the ends of said wrapper down upon the ends respectively of said article or stack of articles.

15. In an article wrapping machine, the combination with a wrapper supply mechanism of a plurality of wrapping rolls, means carried by one of said rolls to lay the wrapper snugly about said article or articles and means to secure the ends of said wrapper over the ends of said article or stack of articles.

16. In an article wrapping machine, the combination with a wrapper supply mechanism of a plurality of wrapping rolls, means for conveying the article or stack of articles to said rolls and means coöoperating with said rolls and operable directly by the travel of said conveying means to wrapping position, to lay the wrapper snugly about said article or articles and means similarly operated to guide the leading end of said wrapper between said article or articles and the following portion of said wrapper during the wrapping operation.

17. In an article wrapping machine, the combination with a wrapper supply mechanism of a plurality of wrapping rolls, means for moving one of said rolls into and out of wrapping position with respect to the others, means for positively conveying the article or stack of articles into wrapping position by said rolls and means operable by contact of said article or articles therewith in the travel of said conveying means to wrapping position to lay the wrapper snugly about said article or articles and to guide the leading end of said wrapper between the said article or articles and the following portion of the wrapper during the wrapping operation.

18. In an article wrapping machine, the combination with a wrapper supply mechanism of a plurality of wrapping rolls, means for swinging one of said rolls into and out of operative position with respect to the others, means coöoperating with said rolls to lay the wrapper snugly about said article or articles, and to guide the leading end of said wrapper between said article or articles and the following portion of the wrapper during the wrapping operation, and means for positively conveying the article or stack of articles into wrapping position between said rolls constructed and arranged to cause said articles to move said wrapper laying and guiding means from article receiving position into operative position during the travel of said article or articles to operative position.

19. In an article wrapping machine, the combination with a wrapper supply mecha-

nism of a plurality of wrapping rolls, one of said rolls being movable into and out of operative position with respect to the others, means carried by said movable roll to lay the wrapper snugly about said article or articles and to guide the leading end of said wrapper between said article or articles and the following portion of said wrapper during the wrapping operation, and means for conveying the article or stack of articles to wrapping position constructed and arranged to cause said articles to move said wrapper laying and guiding means from article receiving position into operative position.

20. In an article wrapping machine, the combination with a wrapper supply mechanism of a plurality of wrapping rolls, one of said rolls being movable into and out of operative position with respect to the others, a member carried by said movable roll to lay said wrapper smoothly about said article or articles and a second member also carried by the movable roll and adapted to guide the leading end of said wrapper between said article or articles and the following portion of said wrapper during the wrapping operation and means to convey articles to wrapping position between said rolls constructed and arranged to cause said articles to move said members from article receiving position to operative position.

21. In an article wrapping machine, the combination with a wrapper supply mechanism of a plurality of wrapping rolls, one of said rolls being movable into and out of operative position with respect to the others, wrapper laying and tucking mechanism carried by said movable roll and comprising a frame having a member adapted to lay said wrapper snugly about said article or articles and a second member adapted to guide the leading end of said wrapper between said article or articles and the following portion of the wrapper during the wrapping operation, and means for conveying an article or stack of articles to operative position between said rolls constructed and arranged to cause said articles to move said laying and tucking mechanism from article receiving position to operative position during the travel of the article or articles to wrapping position.

22. In an article wrapping machine, the combination with a wrapper supply mechanism of a plurality of wrapping rolls, one of said rolls being constructed and arranged to swing into and out of operative position with respect to the others, wrapper laying and tucking mechanism carried by said swinging roll and comprising a frame rotatably mounted thereon, said frame having a member adapted to lay said wrapper smoothly about said article or articles and a second member adapted to guide the leading

end of said wrapper between the said article or articles and the following portion of said wrapper during the wrapping operation, and means for conveying an article or stack of articles to wrapping position, constructed and arranged to cause said article or articles during the travel to wrapping position to

engage said laying and tucking mechanism and to rotate the same from article receiving position into operative position.

CHARLES S. BATDORF.
